[57] CLAIM

The ornamental design for a mattress insert, as shown and described.

DESCRIPTION

FIG. 1 is a top plan view of a mattress insert showing our new design, the bottom plan view being a mirror image thereof;

FIG. 2 is a top right perspective view thereof;

FIG. 3 is a top plan view of a modified form of our new design, the bottom plan view being a mirror image thereof; and

FIG. 4 is a top right perspective view of the same modified form.

Fig.1.

Fig.2.

Fig.3.

Fig.4.
